United States Patent Office.

JOHN F. GOLDTHWAIT, OF BOSTON, MASSACHUSETTS.

Letters Patent No. 68,361, dated September 3, 1867.

IMPROVEMENT IN BUTTONERS FOR SHOES.

The Schedule referred to in these Letters Patent and making part of the same.

TO ALL WHOM IT MAY CONCERN:

Be it known that I, JOHN F. GOLDTHWAIT, of Boston, in the county of Suffolk, in the State of Massachusetts, have invented a new and improved Buttoner for buttoning shoes, gloves, and similar articles; and I do hereby declare that the following is a full and exact description thereof, reference being had to the accompanying drawings, and to the letters of reference marked thereon.

The nature of my invention consists in so constructing the buttoner that there shall be no broken surface on either side to catch in the button-hole, and yet have an opening of sufficient size to receive the button.

To enable others skilled in the art to make and use my invention, I will proceed to describe its construction and operation.

I construct my buttoner of wire, bent in form, as seen in the drawings, (or it may be cut from sheet metal of same form,) and the same is provided with a suitable handle, and is firmly secured to it by being riveted at the extreme end of the handle.

Figure 1 represents a top view of the buttoner, and

Figure 2, an edge view of same.

A is the metallic portion of the buttoner, B the handle, C the opening for the button, d the opening suited to the eye of the button, e the button, f the eye of same, and g the cloth or other material to which it is secured.

The operation is as follows: The extreme end D is inserted into the button-hole of the article to be buttoned, and forced through up to the handle B, when the button is received through the opening C; the motion is then changed to the opposite direction, which carries the eye f of the button e to d, as seen in the drawings, fig. 2. The motion being continued, the button is drawn through the button-hole, which completes the buttoning, and the buttoner is disengaged through the opening C.

This buttoner is particularly adapted to the buttoning of gloves, shoes, and similar articles, and supplies a want long felt in the community. It is simple, yet effective, not liable to get out of order, and can be made sufficiently small to carry in the vest-pocket.

What I claim as my invention, and desire to secure by Letters Patent, is—

A buttoner, substantially as described, consisting of a continuous loop, enlarged at C, for the purpose of receiving the button, and narrowed at d to suit the eye of the button.
